UNITED STATES PATENT OFFICE.

WILLIAM L. ATKINSON, OF EDMONDS, WASHINGTON.

GRIP RATCHET.

Application filed November 22, 1926. Serial No. 150,125.

This invention relates to a gripping device and aims to provide novel means whereby the shaft with which the gripping device is employed may be readily retarded in its movement, ratcheted or stopped at the will of the operator.

An important object of the invention is to provide a gripping device wherein the grip shoes thereof will be evenly applied throughout the circumference of the drum, thereby reducing strain on the machinery with which the device is used, to the minimum.

Another object of the invention is to provide means whereby the shoe which is sectional in formation may be adjusted when the same becomes worn to lose its gripping qualities.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a side elevational view of the device.

Figure 2 is a plan view thereof.

Figure 3 is a transverse sectional view through the device.

Referring to the drawing in detail, the reference character 5 indicates the shaft to which the gripping device is applied which shaft forms a part of machinery not shown.

The reference character 6 indicates a brake drum which is secured to the shaft by means of the pin 7 that fits in the opening of the hub of the drum, as clearly shown by Figure 2.

The periphery of the drum which is indicated at 8 is substantially V-shaped to accommodate the inclined surfaces 9 of the sectional grip shoe embodying sections 10, 11 and 12, the grip shoes being pivotally connected by means of the pins 13.

The section 12 of the shoe is provided with spaced extensions 14 that are provided with openings to receive the bolt 14' which provides a pivot for the curved supporting member 15 of the grip actuating mechanism.

This curved supporting member 15 is provided with a right angled extremity 16

formed with threaded openings to receive the adjusting bolts 17 which engage the shoulder 18 of the grip section 10 as clearly shown by Figure 1 so that the shoe may be adjusted with respect to its drum. 60

Bolts 19 extend laterally from the sections 10 and 12 and are disposed directly in a line with each other where they support the coiled spring 20 that has its ends connected 65 with the bolts so that the sections of the shoe are normally held in position to be readily operated, and to insure against lost motion at the time of operating the grip.

Associated with the curved supporting 70 member 15 is an operating lever 21 that has one end thereof bifurcated and formed with openings to receive the shaft 5 so that the lever may swing on the shaft.

A link 22 has pivotal connection with one 75 end of the curved supporting member 15 and has pivotal connection with the lever 21 by means of the extension 23 forming a part of the link 22, the bolt 24 which passes through the extension 23 and through the bifurcated portion of the lever 21 acting as a pivot for the link.

Bolt 25 connects the link to the curved supporting member 15 to permit of pivotal movement of the link with respect to the 85 member 15. From the foregoing it will be obvious that should it be desired to apply the grip, it is only necessary to operate the lever to cause the curved supporting member 90 15 to rock, exerting a pressure on the sectional grip shoe to move the sections of the grip shoe into gripping relation with the drum 6.

I claim:

1. In a device of the character described, 95 a drum, a shaft on which the drum is secured, a shoe including a plurality of pivotally connected sections, one of the sections having a pair of curved extensions, a supporting member positioned between the curved extensions and pivotally connected therewith, adjusting screws carried by the supporting member, a shoulder carried by one of the sections and engaged by the screws, said screws adapted to move the shoe 100 with respect to the drum to adjust it, and a lever for operating the shoe. 105

2. In a device of the character described, 110 a grip drum, a shaft on which the drum is secured, a grip shoe including a plurality of pivotally connected sections, a curved member having pivotal connection with one of

the sections and having a right angled end portion, adjusting screws extending through the right angled end portion and engaging one of the shoe sections to adjust the shoe 5 with respect to the drum, and means for operating the shoe.

3. In a device of the character described, a drum, a curved supporting member positioned around the drum, a shoe including a 10 plurality of pivotally connected sections, one of said sections being pivotally connected to the supporting member, means carried by the supporting member and contacting with one of the sections for adjusting the sections 15 with respect to the drum, a lever, and a link connecting the lever to the supporting member so that movement of the lever will move

the supporting member to cause the shoe to grip the drum.

4. In a device of the character described, 20 a drum, a shaft on which the drum is mounted, a curved supporting member, a lever mounted on the shaft, means for pivotally connecting the supporting member to the lever, a sectional shoe having one of its ends 25 pivotally connected with the supporting member, means for adjusting the opposite end of the shoe with respect to the drum, and coiled springs carried by the shoe for normally urging the shoe into engagement with 30 the drum.

In testimony that I claim the foregoing as my own, I have hereto affixed my signature.

WILLIAM L. ATKINSON.
